United States Patent Office.

J. M. WILLBUR, OF CLEVELAND, OHIO.

Letters Patent No. 82,463, dated September 22, 1868; antedated September 16, 1868.

IMPROVEMENT IN MACHINE FOR FORMING STEREOTYPE-PLATES.

The Schedule referred to in these Letters Patent and making part of the same.

To all whom it may concern:

Be it known that I, J. M. WILLBUR, of Cleveland, county of Cuyahoga, in the State of Ohio, have invented a new and improved Machine for Forming Cylindrical Stereotype and other Plates; and I do hereby declare that the following is a full and exact description thereof, reference being had to the accompanying drawings, and to the letters of reference marked thereon.

Figure 1 is a plan view.

Figure 2 is an end view.

Figure 3 is a longitudinal section.

Figure 4 is a curved stereotype-plate, to be used on hand-stamp or cylinder-presses.

Figure 5 is the same plate before bent.

The nature of this improvement relates to the construction and arrangement of a machine for bending or forming stereotype or other plates of metal into curved or cylindrical form.

The construction and arrangement of my machine are as follows, and consist of a bed-piece, A, of suitable size, and may be made of suitable material, upon two opposite sides of which are two upright parts, B B, which form the supports and contain the boxes for the journals of the roller C. Upon the top of the uprights B B are fixed the caps b b by means of the pins e, e, and e'. The pins e' may be withdrawn and the caps turned up, so that the roller C may be taken out when desired. The roller C has a milled or file-cut surface, the object of which is to prevent the slipping of the plates while the roller is being turned in the process of bending the plates.

D is an apron or flap, of sheet-iron or other suitable material, attached to the roller C; the roller C being divided into halves and secured together by the screws d d, the edge of the apron D being clamped between the two halves of the roller C.

E is an adjustable sliding bed, provided with bevelled guides, f f, on the under side. Upon the end next to the roller C, the sliding bed E has an upright part, g, the surface next to the roller being concave, and sufficiently larger than the roller to allow space for the

passage of the apron D and plate to be bent upon the roller.

H is a thumb set-screw, playing in the standard i, and is attached to the sliding bed E for the purpose of adjusting it in relation to the roller C, and adapting the space between them to the thickness of the plates to be bent.

L is a crank upon the roller C, by which it is turned. The operation of this machine is as follows:

Upon the apron D, which lies upon the bed E, there is put one or more thicknesses of thick paper, leather, or other suitable material, to protect the face of the type from being bruised. Then a plate, similar to the one seen at fig. 5, is laid upon the paper, face downward; then, by turning the crank L, the roller carries the apron and the plate to be bent around and between it and the upright, g, and perfectly forms the plate around the roller, like that seen at fig. 4. By this means the surface of the type is made to conform to the curvature as well as the thinner parts. Plates of any size may be bent in this manner, either for small or large printing-cylinders, and making the printing-face of the type conform perfectly to the curvature, whether they be single type, or large cuts, or whole pages of reading-matter. It is well adapted, also, to the forming of sheets of metal of any kind in cylindrical forms for manufacturing-purposes.

I claim—

1. The roller C, having a milled or file-cut circumferential surface, for the purpose described, in combination with the apron D, arranged and operating as and for the purpose set forth.

2. The sliding bed E, having a head or upright, g, with its curved surface and the adjusting set-screw H, in combination with the roller C and apron D, all constructed and operating as described, and for the purpose set forth.

J. M. WILLBUR.
